UNITED STATES PATENT OFFICE

2,127,438

AIR COOLED CONDENSER

Christian Steenstrup, Schenectady, N. Y., assignor to General Electric Company, a corporation of New York

Application January 18, 1936, Serial No. 59,755

10 Claims. (Cl. 257—36)

My invention relates to air cooled condensers for refrigerating machines. More particularly my invention relates to air cooled condensers for refrigerating machines in which a tubular sheet metal member having a condensing chamber therein is provided, an annulus of heat conducting fins or other intermediate supporting member being arranged within the periphery of the tubular member. The tubular member and intermediate supporting member are ordinarily pressed on a cylindrical compressor casing or similar main supporting member. I have found, however, that when such condensers are produced by large scale quantity-production factory methods that the diameters of the supporting casing and the tubular member as well as the dimensions of the fins or other intermediate supporting member vary sufficiently that a relatively wide variation in pressure is required to press the parts together. In addition, if an unusually great pressure is used to press the parts together, they may be subjected to excessive strains which will cause them to be ruptured or materially weakened.

It is an object of my invention to provide an air cooled condenser of the type described comprising a tubular member having a condensing chamber therein and mounted on an intermediate supporting member surrounding a main supporting member and an arrangement which readily provides an increase in the circumferential length of the tubular member due to the internal stretching forces to which it is subjected, the stretching in the tubular member being localized in a particular part thereof.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a side elevation of a portion of a refrigerator cabinet and refrigerating machine therefor provided with an air cooled condenser embodying my invention; Fig. 2 is a plan view of the refrigerator shown in Fig. 1; Fig. 3 is an enlarged elevation, partly in section, of the rear portion of the condenser shown in Fig. 1, and Fig. 4 is a fragmentary sectional view along the line 4—4 of the condenser shown in Fig. 3.

Referring to the drawing, in Fig. 1 I have shown a household refrigerator cabinet having

a refrigerating unit provided with an air cooled condenser embodying my invention. In this unit a compressor and electric driving motor therefor are arranged in a cylindrical hermetically sealed steel casing 10 mounted on a removable cabinet top 11. Gaseous refrigerant, such as sulphur dioxide, is compressed by the motor driven compressor in the casing 10 and is supplied therefrom to a tubular member 12 having an air cooled condensing chamber therein, which tubular member surrounds the casing 10 and is supported on a zigzag annulus of fins 13 interposed between the tubular member and the casing. The compressed gaseous refrigerant flowing through the condensing chamber in the tubular member 12 is cooled and liquefied by air flowing upwardly over the surfaces of the tubular member 12 and between the tubular member and the casing 10 over the surfaces of the heat conducting fins 13. The refrigerant so liquefied flows to a flow controlling float valve 14 from which it is supplied through a liquid line 15 to an evaporator 16 suspended below the cabinet top 11 within a food storage compartment 17, which the evaporator is adapted to cool. The liquid refrigerant is vaporized in the evaporator 16 by the absorption of heat from the cooling compartment 17 and is collected in a longitudinal cylindrical header 18 above the level of the liquid refrigerant therein, the header 18 being normally maintained about half full of liquid refrigerant. The vaporized refrigerant thus collected in the header 18 is returned to the compressor in the casing 10 through a suction conduit 19 and the cycle described is repeated and continued until the temperature of the cooling compartment 17 is lowered to a desired value.

The tubular member 12, which is preferably cylindrical in form, includes an outer sheet or portion of metal 20, and upper and lower inner portions or sheets of metal 21 and 22, respectively. Upper and lower elongated sinuous indentations 23 and 24 are provided in the outer sheet of metal 20. A complementary elongated sinuous indentation 25 is formed in the lower inner sheet of metal 22, the indentation 25 registering with the indentation 24. A similar complementary elongated sinuous indentation is formed in the upper inner sheet of metal 21 and arranged in registry with the indentation 23. The indentations are preferably stamped in the inner and outer sheets of metal by suitable dies. A plurality of rows of narrow transverse slots 26 are punched or otherwise formed in an extended end portion 27 of the outer sheet of metal 20.

The transverse slots 26 are provided in order to provide a relatively weak transverse section in the tubular member which permits a limited and localized increase in the peripheral length of the completed tubular member 12, as is hereinafter more fully described. The stamping and punching operations, referred to above, are preferably completed before the sheets of metal 20, 21 and 22 are assembled to form the completed tubular member 12.

In assembling the sheets of metal 20, 21 and 22 to form the tubular member 12, the inner sheets of metal 21 and 22 are preferably arranged flat in face contact with the inner surface of the outer sheet of metal 20 and in such position that the end portion 27 of the outer sheet 20 extends beyond the adjacent ends of the inner sheets 21 and 22. The sheets of metal 21 and 22 are then hermetically secured to the outer sheet 20 by line welds or a series of closely spaced spot welds, which extend about the peripheries of the sheets 21 and 22 and along the edges of the indentations 23, 24 and 25 throughout their length. After having been thus secured together, the sheets of metal are bent into the form of a cylinder and the adjacent edges thereof are secured together. The end part of the extended portion 27 of the outer sheet 20 is preferably lapped over the opposite end portion of the sheet 20, the transverse edge of the portion 27 being arranged in abutting relation with the adjacent transverse edge of the inner sheet 22 as best shown in Fig. 4. The overlapping portions of the sheet 20 are then welded or otherwise rigidly secured together.

A rectangular sheet of metal is bent into the form of a zigzag series of fins 13 and these fins are then arranged within the tubular member 12 so that the fins 13 and tubular member 12 constitute an annulus. The fins 13 form an intermediate supporting member between the tubular member 12 and the main supporting member or casing 10. The annulus thus formed is then pressed on to the casing or supporting member 10. The pressing operation is preferably carried out in the hydraulic press and for the machine illustrated a pressure of about seven tons is required. The transverse slots 26 formed in the end portion 27 of the outer sheet of metal 20 permit a limited amount of stretching in the end portion 27 so that a deformable joint is formed between the adjacent ends of the sheet of metal 20. The length and number of the slots 26, as well as the distance therebetween, is so proportioned that the widening of the slots and consequent stretching of the total length of the end portion 27 will take place only when a predetermined force tending to increase the peripheral length of the tubular member 12 is applied thereto. By means of such an arrangement I have found that the annulus formed of the fins 13 and tubular member 12 may be pressed on to the casing 10 by substantially uniform pressure, even though the casing 10 is somewhat oversized in diameter, the fins 13 too long, and the tubular member 12 somewhat undersized in diameter. It is desirable that a uniform pressure be used in assembling the parts of the condenser described above both in order to limit the pressure required of the assembly press and also in order to avoid excessive strains on the parts. Moreover, an excessive internal pressure tending to increase the peripheral length of the tubular member 12 would tend to flatten the indentations 24 and 25 thus obstructing the flow of refrigerant through the passages formed thereby. In the arrangement

which I have provided, however, substantially all of the stretching in the tubular member 12 is localized in the extended portion 27 of the outer sheet 20 and it will be noted that no refrigerant passages extend across this portion of the tubular member. The arrangement which I have provided to permit a limited and localized increase in peripheral length of the tubular member 12 is especially adapted for use in manufacturing large quantities of condensers by quantity-production methods. When using such methods, the sheet metal parts of the condenser are ordinarily formed in power operated punch presses and the like and, as a consequence, some variations in dimensions are likely to occur due to wearing of the dies or variations in dimensions of replacement of the dies. It should also be noted that the stretching permitted in the extended portion 27 of the sheet 20 by the slots 26 is limited to substantially the exact amount required in order to maintain a uniform pressure during the assembling operation despite the multiplicity of variations in dimensions of the parts which may occur.

While I have shown a particular embodiment of my invention in connection with a compression type refrigerating machine designed for household use, I do not desire my invention to be limited to the particular construction shown and described and I intend in the appended claims to cover all modifications within the spirit and scope of my invention.

I claim:

1. An air cooled condenser for a refrigerating machine comprising a supporting member, a tubular member having a condensing chamber therein and extending about said supporting member and arranged in spaced relation thereto, and means including an intermediate supporting member extending between said first named supporting member and said tubular member for preventing relative movement therebetween, said tubular member having a transverse slot formed therein to provide a limited and localized increase in the peripheral length thereof due to the internal stretching forces to which it is subjected.

2. An air cooled condenser for a refrigerating machine comprising a supporting member, a tubular sheet metal member having a condensing chamber therein and extending about said supporting member and arranged in spaced relation thereto, means including an intermediate supporting member extending between said first named supporting member and said tubular member for preventing relative movement therebetween, said tubular member including complementary inner and outer tubular portions of sheet metal defining an extended refrigerant passage therebetween, means for hermetically securing said portions of sheet metal together, and means including a deformable joint for securing the adjacent ends of at least one of said portions of sheet metal together to provide a limited and localized increase in the peripheral length of said tubular member due to the internal stretching forces to which it is subjected.

3. An air cooled condenser for a refrigerating machine comprising a supporting member, an annulus of fins extending about said supporting member, and a tubular member having a condensing chamber therein and positioned on said fins so as to constitute an annulus, said tubular member having a transverse slot formed therein to provide a limited and localized increase in the

circumferential length thereof due to the internal stretching forces to which it is subjected.

4. An air cooled condenser for a refrigerating machine comprising a supporting member, an annulus of fins extending about said supporting member, and a tubular sheet metal member having a condensing chamber therein and positioned on said fins so as to constitute an annulus, said tubular member including complementary inner and outer tubular portions of sheet metal having an extended refrigerant passage formed therebetween, and means for hermetically securing said portions of sheet metal together, at least one of said portions of sheet metal having a transverse slot formed therein to provide a limited and localized increase in the circumferential length of said tubular member due to the internal stretching forces to which it is subjected.

5. An air cooled condenser for a refrigerating machine comprising a supporting member, an annulus of fins extending about said supporting member, and a tubular sheet metal member having a condensing chamber therein and positioned on said fins so as to constitute an annulus, said tubular member including complementary inner and outer tubular sheets of metal, and means for hermetically securing said sheets of metal together in face contact, at least one of said sheets of metal having an indentation formed therein cooperating with the other of said sheets of metal to form an extended refrigerant circulatory passage therebetween, an end portion of one of said sheets of metal extending beyond the adjacent end of the other of said sheets of metal, said end portion of said one sheet of metal being secured to the opposite end of said one sheet of metal, said end portion of said one sheet of metal having a plurality of rows of transverse slots formed therein and arranged in staggered relation to provide a limited and localized increase in the length thereof due to the internal stretching forces to which said tubular member is subjected.

6. An air cooled condenser for a refrigerating machine including a tubular member having a condensing chamber therein of substantially annular configuration, and a support, said tubular member extending about said supporting member and being frictionally secured thereto and having a relatively weak transverse section therein to facilitate a limited and localized increase in the circumferential length thereof due

to the internal stretching forces to which it is subjected.

7. An air cooled condenser for a refrigerating machine comprising a supporting member, a tubular member having a condensing chamber therein and extending about said supporting member and arranged in spaced relation thereto, and means including an intermediate supporting member extending between said first named supporting member and said tubular member for preventing relative movement therebetween, said tubular member having a plurality of rows of transverse slots formed therein and arranged in staggered relation to provide a limited and localized increase in the peripheral length thereof due to the internal stretching forces to which it is subjected.

8. An air cooled condenser for a refrigerating machine including a tubular member having a condensing chamber therein, said tubular member having a relatively weak transverse section therein to facilitate a limited and localized increase in the peripheral length thereof due to the internal stretching forces to which it is subjected.

9. An air cooled condenser for a refrigerating machine including a tubular member having a condensing chamber therein extending about a major portion of the periphery of said tubular member and leaving a minor portion of the periphery thereof free of said condensing chamber, and means including a transverse slot formed in said minor portion of the periphery of said tubular member for facilitating a limited and localized increase in the peripheral length of said tubular member and occurring in said minor portion of the periphery thereof due to the internal stretching forces to which it is subjected.

10. An air cooled condenser for a refrigerating machine including complementary inner and outer tubular portions of sheet metal defining an extended refrigerant passage therebetween, means for hermetically securing said portions of said sheet metal together, and means including a deformable joint for securing the adjacent ends of at least one of said portions of sheet metal together to provide a limited and localized increase in the peripheral length thereof due to the internal stretching forces to which it is subjected.

CHRISTIAN STEENSTRUP.
